US0D1078029S

(12) **United States Design Patent** (10) **Patent No.:** **US D1,078,029 S**
Chen et al. (45) **Date of Patent:** **** Jun. 3, 2025**

(54) **EARPLUG**

(71) Applicant: **Jiayin Zhichuang Technology (Shenzhen) Co., Ltd**, Shenzhen (CN)

(72) Inventors: **Zhihao Chen**, Shenzhen (CN); **Guoyou Chen**, Shenzhen (CN)

(73) Assignee: **Jiayin Zhichuang Technology (Shenzhen) Co., Ltd**, Shenzhen (CN)

(**) Term: **15 Years**

(21) Appl. No.: **29/970,908**

(22) Filed: **Oct. 31, 2024**

(30) **Foreign Application Priority Data**

Aug. 8, 2024 (CN) 202430502082.4

(57) **CLAIM**

The ornamental design for an earplug, as shown and described.

DESCRIPTION

FIG. 1 is a front perspective view of an earplug, showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

(Continued)

The broken lines in the drawings illustrate the portions of the earplug, which form no part of the claimed design.

1 Claim, 8 Drawing Sheets
